UNITED STATES PATENT OFFICE.

RALPH L. PECK, OF WASHINGTON, DISTRICT OF COLUMBIA.

DESIGN FOR A BADGE OR SIMILAR ARTICLE.

SPECIFICATION forming part of Design No. 34,988, dated August 27, 1901.

Application filed July 18, 1901. Serial No. 68,855. Term of patent 3½ years.

To all whom it may concern:

Be it known that I, RALPH L. PECK, of Washington, in the District of Columbia, have invented and produced a new and useful Design 5 for Badges or Similar Articles, of which the following is a specification, reference being had to the accompanying drawing, forming a part thereof, and which represents a badge embodying the design.

- 10 As shown in the drawing, my design consists in the representation of three interlinked figures *a*, *b*, and *c*, arranged one above the other, and the figure or representation of a 15 buffalo *l*, arranged horizontally beneath the lowermost figure, with its upper surface, representing the back of the animal, joined to the bottom of the figure *c*. The three figures are each continuous in outline and composed of two parallel lines, the figure *a* comprising 20 a vertical line *a'*, which curves at its upper end back on itself, forming a loop *a*², from which point the line extends horizontally outward and is then curved downward and inward toward the line *a'*, where it is again 25 bent back on itself, forming an eye *a*³, from which point the line extends downward and outward and terminates in an eye *a*⁴, the lower part of the figure presenting two eyes

separated some distance from each other. The figure *b* is of general **U** form, with its 30 upper ends curved in the form of eyes *b*¹, which are interlinked with the eyes on the lower part of the figure *a*. The bottom of the figure *b* is curved in the form of an eye *b*². The figure *c* comprises two downwardly-extending diverging lines *c'*, which join each other at the upper ends and extend through the eye *b*¹. At their lower ends these lines are curved outward, upward, and then across the diverging portions and join each other, 40 the lower part of the figure thus presenting two large loops *c*². The bottoms of these loops join the upper surface of the figure of the 45 buffalo *l*, which is arranged horizontally beneath the figure *c*.

Having thus described my invention, what I claim is—

The design for a badge or similar article as herein shown and described.

In testimony whereof I hereunto set my 50 hand, this 1st day of July, 1901, in the presence of two attesting witnesses.

RALPH L. PECK.
